(57) **ABSTRACT**

A food container with condiment compartment has bottom portion, and a top portion, and a hinge portion. The bottom portion includes a bottom panel, two oppositely disposed sidewall panels, a front panel, and a rear panel. The top portion includes a top panel, two oppositely disposed sidewall panels, a front panel, and a rear panel. The hinge portion has a first trough panel extending from the rear panel of the bottom portion, and a second trough panel extending from the rear panel of the top portion. The hinge portion also has two oppositely disposed end panels that are joined to the first trough panel and joined to the second trough panel. The combination of the first trough panel, the second trough panel, and the two end panels forms a condiment compartment or open trough positioned between the bottom portion and the top.

FIG. 4

FIG. 7

1

FOOD CONTAINER WITH CONDIMENT COMPARTMENT

CROSS REFERENCE TO RELATED APPLICATIONS

This is a continuation in part of U.S. patent application Ser. No. 18/198,001 filed May 16, 2023 and entitled Food Container With Condiment Compartment.

STATEMENT REGARDING FEDERALLY SPONSORED RESEARCH OR DEVELOPMENT

Not applicable.

THE NAMES OF THE PARTIES TO A JOINT RESEARCH AGREEMENT

Not applicable.

BACKGROUND OF THE INVENTION

This section is intended to introduce various aspects of the art, which may be associated with exemplary embodiments of the present disclosure. This discussion is believed to assist in providing a framework to facilitate a better understanding of particular aspects of the present disclosure. Accordingly, it should be understood that this section should be read in this light, and not necessarily as admissions of prior art.

FIELD OF THE INVENTION

The present inventive concept relates to the field of food containers. More particularly, the invention relates to a food container having a condiment compartment.

TECHNOLOGY IN THE FIELD OF THE INVENTION

Many fast foods, such as hamburgers, French fries, chicken sandwiches, tacos, chick fingers, and the like, are served by fast food restaurants in paperboard containers. These containers typically includes a bottom tray or portion and a top cover or portion that is hinged coupled to the bottom tray along a common fold line.

Many of these foods are eaten with condiments such as ketchup, mustard, special sauces, and the like. The problem is that while eating in a car or on the move it is difficult to use these condiments with the food as there is no separation between the food item and the condiment. Therefore, a person sometimes skips the use of the condiment and must settle for eating the food item without such.

Accordingly, a need exists for a food container having the capability of holding condiments separate from the food item. It is to the provision of such therefore that the present invention is primarily directed.

BRIEF SUMMARY OF THE INVENTION

A food container comprises a first portion having a bottom panel, two oppositely disposed first sidewall panels, a first front panel, and a first rear panel, a second portion having a top panel, two oppositely disposed second sidewall panels, a second front panel, and a second rear panel, and a hinge portion coupled to the first portion along a first fold line and coupled to the second portion along a second fold line for pivotal movement of the second portion relative to the first

2

portion between a closed configuration wherein the second portion is in register with the first portion and an open configuration wherein the second portion is not in registered with the first portion, the hinge portion forming a panel extending between the first portion and the second portion when the second portion is positioned in its open configuration, the panel of the hinge portion having at least one condiment container opening therethrough of a select configuration.

10 In another embodiment, a food container comprises a bottom portion having a bottom panel, at least four sidewall panels extending from the bottom panel, and a separator panel mounted for pivotal movement between a closed position flush with one the sidewall panel and an open position distal the one sidewall panel, the separator panel having a central panel and at least one end panel extending from the central panel, the at least one end panel having a bottom edge configured to abut the bottom panel of the bottom portion when the separator panel is in its open position, a top portion having a top panel and at least four sidewalls panels extending from the top panel, and a hinge pivotally coupling the top portion to the bottom portion.

BRIEF DESCRIPTION OF THE DRAWINGS

25 So that the manner in which the present inventions can be better understood, certain illustrations, charts and/or flow charts are appended hereto. It is to be noted, however, that the drawings illustrate only selected embodiments of the 30 inventions and are therefore not to be considered limiting of scope, for the inventions may admit to other equally effective embodiments and applications.

35 FIG. 1 is a perspective view of a food container with condiment compartment embodying principles of the invention in a preferred form, shown in a closed configuration.

FIG. 2 is a perspective view of a food container with condiment compartment of FIG. 1, shown in an open configuration.

40 FIG. 3 is a perspective view of a food container embodying principles of the invention in another preferred form, shown in a closed configuration.

FIG. 4 is a perspective view of the food container of FIG. 3, shown in an open configuration.

45 FIG. 5 is a perspective view of a food container embodying principles of the invention in another preferred form, shown in an open configuration.

FIG. 6 is a perspective view of a food container embodying principles of the invention in another preferred form, shown in an open configuration.

50 FIG. 7 is a bottom view of a food container embodying principles of the invention in yet another preferred form.

DETAILED DESCRIPTION OF CERTAIN EMBODIMENTS

Definitions

For purposes of the present disclosure, it is noted that spatially relative terms, such as "up," "down," "right," "left," "beneath," "below," "lower," "above," "upper" and the like, may be used herein for ease of description to describe one element or feature's relationship to another element(s) or feature(s) as illustrated in the figures. It will be understood that the spatially relative terms are intended to encompass different orientations of the device in use or operation in addition to the orientation depicted in the figures. For example, if the device in the figures is turned

over or rotated, elements described as "below" or "beneath" other elements or features would then be oriented "above" the other elements or features. Thus, the exemplary term "below" can encompass both an orientation of above and below. The device may be otherwise oriented (rotated 90 degrees or at other orientations) and the spatially relative descriptors used herein interpreted accordingly.

Description of Selected Specific Embodiments

With reference next to the drawings, there is a shown a food container with condiment compartment **10** in a preferred form of the present invention, hereinafter references simply as food container **10**.

The food container **10** includes a tray, first or bottom portion **12** and a cover, second or top portion **14**. The top portion **14** is coupled to the bottom portion **12** along a hinge or hinge portion **16**.

The bottom portion **12** includes a bottom panel **22**, two oppositely disposed sidewall panels **24** extending from the bottom panel **22**, a front panel **26** extending from the bottom panel **22**, and a rear panel **28** extending from the bottom panel **22**. The rear panel **28** is coupled to the hinge portion **16** along a first fold or fold line **32**. The front panel **26** may include a tab slot **34** therein. The term "panel" may be used interchangeably with the words "wall", "side", "portion" or "part".

The top portion **14** includes a top panel **38**, two oppositely disposed sidewall panels **40** extending from the top panel **38**, a front panel **42** extending from the top panel **38**, and a rear panel **44** extending from the top panel **38**. The rear panel **44** is coupled to the hinge portion **16** along a second fold or fold line **46**. The front panel **42** may include a tab **48** configured to be received within tab slot **34**.

The hinge portion **16** has a first trough panel **52** extending from the rear panel **28** of the bottom portion **12** along the first fold **32**, and a second trough panel **54** extending from the rear panel **44** of the top portion **14** along the second fold line **46**. The first trough panel **52** and second trough panel **54** are joined together along a third fold or fold line **56**, the third fold line **56** may also be referenced as a bottom fold. The hinge portion **16** also has two oppositely disposed end panels **60**. Each end panel **60** is joined to the first trough panel **52** along a fourth fold or fold line **64** and joined to the second trough panel **54** along a fifth fold or fold line **66**. The fourth and fifth fold lines **64** and **66** may be referenced herein as end folds. Each trough end panel **52** and **54** also has a generally central sixth fold or fold line **68** to allow the end panels **52** and **54** to be folded upon themselves. The sixth fold line **68** may be referenced herein as a central fold. The term "central" or "center" used herein does not require the position to be in the exact center and is meant to include a position that is generally within a central area. The combination of the first trough panel **52**, the second trough panel **54** and the two end panels **60** forms a condiment compartment or open trough **70** (trough having the top open and all sides enclosed) positioned between the bottom portion **12** and the top portion **14** that acts as a condiment compartment for the storage of condiments when the food container is in an unregistered, open configuration, shown in FIG. 2.

In use, with the food container **10** in an open configuration, shown in FIG. 2, food may be placed within the bottom portion **12** and the top portion **14** is pivoted along fold lines **32**, **46** and **56** to its closed position, shown in FIG. 1. The closed configuration being wherein the top portion **14** is in register with the bottom portion **12** so as to essentially close

the container to contain the food therein, i.e., the top edges of the sidewall panels **24**, front panel **26** and rear panel **28** of the bottom portion **12** are positioned closely to or in register with the bottom edges of the sidewall panels **40**, front panel **42** and rear panel **44** of the top portion **14**. The tab **48** may then be placed within the tab slot **34** to maintain the food container **10** in its closed configuration. The food container **10** including the food therein may then be presented to the customer.

10 The customer may subsequently open the food container **10** by pivoting the top portion **14** along fold lines **32**, **46** and **56** to an open configuration, shown in FIG. 2. Through the pivoting motion of the top portion **14** relative to the bottom portion **12** the first trough panel **52** and second trough panel **54** pivot away from each other along the third fold line **56**, thereby forming the open top condiment trough **70**. Simultaneously, the end panels **60** form the ends or end walls of the trough by unfolding or pivoting along the central sixth fold line **68** and pivoting along the fourth and fifth fold lines **64** and **66**. Thus, the condiment trough **70** is automatically formed through the opening of the food container without intervention from the consumer.

An added benefit of the present invention is that the condiment compartment or trough **70** does not take space within the food area of the bottom portion **12**.

25 It should be understood that the hinge portion **16** that extends outwardly from the bottom portion **12** and top portion may be adhered to either the bottom or top portion **12**, **14** with a weak adhesive so that it may be pulled away if the condiment trough **70** is to be utilized or remain in place if the condiment trough **70** is not to be used, as the hinge portion **16** may still act as a hinge between the bottom portion and top portion when adhered to an adjacent rear wall **28** or **44**.

30 With reference next to FIGS. 3 and 4, there is a shown a food container with condiment compartment **10** in another preferred form of the present invention, hereinafter references simply as food container **10**.

35 Here again, the food container **10** includes a tray, first or bottom portion **12** and a cover, second or top portion **14**. The top portion **14** is coupled to the bottom portion **12** along a hinge or hinge portion **16**.

40 The bottom portion **12** includes a bottom panel **22**, two oppositely disposed sidewall panels **24** extending from the bottom panel **22**, a front panel **26** extending from the bottom panel **22**, and a rear panel **28** extending from the bottom panel **22**. The rear panel **28** is coupled to the hinge portion **16** along a first fold or fold line **32**. The front panel **26** may include a tab slot **34** therein.

45 The top portion **14** includes a top panel **38**, two oppositely disposed sidewall panels **40** extending from the top panel **38**, a front panel **42** extending from the top panel **38**, and a rear panel **44** extending from the top panel **38**. The rear panel **44** is coupled to the hinge portion **16** along a second fold or fold line **46**. The front panel **42** may include a tab **48** configured to be received within tab slot **34**.

50 The bottom portion **12** includes a central separator or trough panel **10** extending from the rear panel **28** of the bottom portion **12** along the first fold **32**. Optionally, the trough panel **10** may be coupled to the bottom panel **22**. Two end walls or panels **84** extend from opposite ends of the central trough panel **80** and are each coupled to one sidewall panel **24**. Each end panel **84** includes a central fold or fold line **86** that allows the end panel **84** to be folded upon itself. The combination of the sidewall panel **24**, end panels **84** and central panel **80** forms a condiment compartment or condiment trough **88**.

In use, with the food container 10 in an open configuration, shown in FIGS. 3 and 4, food may be placed within the bottom portion 12 and the top portion 14 is pivoted to its closed position. The closed configuration being wherein the top portion 14 is in register with the bottom portion 12 so as to essentially close the container to contain the food therein, i.e., the top edges of the sidewall panels 24, front panel 26 and rear panel 28 of the bottom portion 12 are positioned closely to the bottom edges of the sidewall panels 40, front panel 42 and rear panel 44 of the top portion 14. The tab 48 may then be placed within the tab slot 34 to maintain the food container 10 in its closed configuration. The food container 10 including the food therein may then be presented to the customer.

The customer may subsequently open the food container 10 by pivoting the top portion 14 along fold lines 32, 46 and 56 to an open configuration, shown in FIG. 3.

The customer may then pivot the trough central panel 80 away from the rear panel 28 so as to open the condiment compartment 88. This movement of the trough central panel 80 unfolds the end panels 84 forming an enclosed compartment. The term enclosed compartment means that the compartment is essentially sealed to prevent leaking of the condiment except through the open top, i.e., there are no openings between the trough central panel 80 and the sidewall panels 24.

Once unfolded, a condiment may be poured into the condiment compartment 88.

With reference next to FIG. 5, there is shown a food container with condiment compartment 10 in another preferred form of the present invention, hereinafter references simply as food container 10.

Here again, the food container 10 includes a tray, first or bottom portion 12 and a cover, second or top portion 14. The top portion 14 is coupled to the bottom portion 12 along a hinge or hinge portion 16.

The bottom portion 12 includes a bottom panel 22, two oppositely disposed sidewall panels 24 extending from the bottom panel 22, a front panel 26 extending from the bottom panel 22, and a rear panel 28 extending from the bottom panel 22. The rear panel 28 is coupled to the hinge portion 16 along a first fold or fold line 32. The front panel 26 may include a tab slot 34 therein.

The top portion 14 includes a top panel 38, two oppositely disposed sidewall panels 40 extending from the top panel 38, a front panel 42 extending from the top panel 38, and a rear panel 44 extending from the top panel 38. The rear panel 44 is coupled to the hinge portion 16 along a second fold or fold line 46. The front panel 42 may include a tab 48 configured to be received within tab slot 34.

The bottom portion 12 includes a central separator or trough panel 80 extending from the rear panel 28 of the bottom portion 12 along the bottom fold or fold line 90. Optionally, the trough panel 80 may be coupled to the bottom panel 22. Two end walls or panels 84 extend from opposite ends of the central trough panel 80. Each end panel 84 includes an end fold or fold line 86 that allows the end panel 84 to be folded so that the end panel 84 overlaps the adjacent sidewall panel 24. The combination of the sidewall panel 24, end panels 84 and central panel 80 forms a condiment compartment or condiment trough 88.

Each end panel 84 is generally triangular in shape and includes has a lower or bottom edge 94 which when the condiment compartment 88 is in an open configuration abuts the bottom panel 22 to prevent further opening of the trough

panel 80 and provide support to the trough panel 80 under the weight of condiments placed within the condiment compartment 88.

In use, with the food container 10 in an open configuration, shown in FIG. 5, food may be placed within the bottom portion 12 and the top portion 14 is pivoted to its closed position. The closed configuration being wherein the top portion 14 is in register with the bottom portion 12 so as to essentially close the container to contain the food therein, i.e., the top edges of the sidewall panels 24, front panel 26 and rear panel 28 of the bottom portion 12 are positioned closely to the bottom edges of the sidewall panels 40, front panel 42 and rear panel 44 of the top portion 14. The tab 48 may then be placed within the tab slot 34 to maintain the food container 10 in its closed configuration. The food container 10 including the food therein may then be presented to the customer.

The customer may subsequently open the food container 10 by pivoting the top portion 14 along fold lines 32, 46 and 56 to an open configuration, shown in FIG. 5.

The customer may then pivot the trough central panel 80 away from the rear panel 28 so as to open the condiment compartment 88. This movement of the trough central panel 80 unfolds the end panels 84 forming an enclosed compartment. The term enclosed compartment means that the compartment is essentially sealed to prevent leaking of the condiment except through the open top, i.e., there are no openings between the trough central panel 80 and the sidewall panels 24. The abutment of the bottom edge 94 of the end panels 84 against the bottom panel bolsters or strengthens the condiment compartment 88.

Once unfolded, a condiment may be poured into the condiment compartment 88.

The entire food container 10 may be made of a single sheet of paperboard stock that is cut and folded to form the food container 10 shape shown in the drawings.

The food container 10 is formed so that a plurality of food containers 10 may be nested one within the next to provide a compact stack of food containers.

With reference next to FIG. 6, there is shown a food container with condiment compartment 10 in a preferred form of the present invention, hereinafter references simply as food container 10.

The food container 10 includes a tray, first or bottom portion 12 and a cover, second or top portion 14. The top portion 14 is coupled to the bottom portion 12 along a hinge or hinge portion 16.

The bottom portion 12 includes a bottom panel 22, two oppositely disposed sidewall panels 24 extending from the bottom panel 22, a front panel 26 extending from the bottom panel 22, and a rear panel 28 extending from the bottom panel 22. The rear panel 28 is coupled to the hinge portion 16 along a first fold or fold line 32. The front panel 26 may include a tab slot 34 therein. The term "panel" may be used interchangeably with the words "wall", "side", "portion" or "part".

The top portion 14 includes a top panel 38, two oppositely disposed sidewall panels 40 extending from the top panel 38, a front panel 42 extending from the top panel 38, and a rear panel 44 extending from the top panel 38. The rear panel 44 is coupled to the hinge portion 16 along a second fold or fold line 46. The front panel 42 may include a tab 48 configured to be received within tab slot 34.

The hinge portion 16 has a first trough panel 52 extending from the rear panel 28 of the bottom portion 12 along the first fold 32, and a second trough panel 54 extending from the rear panel 44 of the top portion 14 along the second fold

line 46. The first trough panel 52 and second trough panel 54 are joined together along a third fold or fold line 56, the third fold line 56 may also be referenced as a middle fold. The hinge portion 16 also has two generally rectangular shaped condiment tray or package openings 96 extending through the hinge portion 16, although the hinge portion 16 may include one or more such package openings 96. Each package opening 96 may also extend through only one of the two trough panels 52 or 54. The package openings 96 are sized and shaped, or otherwise configured, to receive a condiment package 100 corresponding to the shape of the package opening 96. Such condiment packages typically includes a small receptacle area having a peripheral rim 102 to prevent the condiment package 100 from falling completely through the package opening 96, i.e., the condiment package 100 is held in the package opening 96 with its peripheral rim 102 resting upon the hinge portion 16.

A weak or releasable adhesive 98 may be placed between the first and second trough panels 52 and 54 so that the hinge portion 16 is maintained in a closed configuration until needed, when a customer would then separate the first and second trough panels 52 and 54 for expanded use as a condiment holder. This will aid in maintaining the food container in a compact configuration for storage and nesting capabilities.

In use, with the food container 10 in an open configuration, shown in FIG. 6, food may be placed within the bottom portion 12 and the top portion 14 is pivoted along fold lines 32, 46 and 56 to its closed position. The closed configuration being wherein the top portion 14 is in register with the bottom portion 12 so as to essentially close the container to contain the food therein, i.e., the top edges of the sidewall panels 24, front panel 26 and rear panel 28 of the bottom portion 12 are positioned closely to or in register with the bottom edges of the sidewall panels 40, front panel 42 and rear panel 44 of the top portion 14. The tab 48 may then be placed within the tab slot 34 to maintain the food container 10 in its closed configuration. The food container 10 including the food therein may then be presented to the customer.

The customer may subsequently open the food container 10 by pivoting the top portion 14 along fold lines 32, 46 and 56 to an open configuration, shown in FIG. 6. If the condiment holding capabilities of the food container 10 are desired, the customer simply pulls or pivots the first trough panel 52 and second trough panel 54 away from each other along the third fold line 56, thereby forming the open top condiment table or tray 70. A corresponding condiment package 100 may then be placed within the opening 96 with the peripheral rim 102 resting upon the hinge portion 16. The rigidity of the condiment package 100 may aid in maintaining the hinge portion 16 in an open configuration.

An added benefit of the present invention is that the condiment compartment or trough 70 does not take space within the food area of the bottom portion 12.

It should be understood that the hinge portion 16 that extends outwardly from the bottom portion 12 and top portion may also be adhered to either the bottom or top portion 12, 14 with a weak adhesive so that it may be pulled away if the condiment trough 70 is to be utilized or remain in place if the condiment trough 70 is not to be used, as the hinge portion 16 may still act as a hinge between the bottom portion and top portion when adhered to an adjacent rear wall 28 or 44. The hinge portion 16 may also be designed to include two hinge portions (a right hinge portion 16A and a left hinge portion 16B) on either side of the package opening 96 (shown as one opening in FIG. 7) so that one hinge portion is releasably adhered to only one side of the food

container, i.e., one hinge portion is adhered to the top portion and the other hinge portion is adhered to the bottom portion. This configuration aids in the nesting of the food container.

It thus is seen that a food container is now provided which overcomes problems associated with food containers of the prior art. It should of course be understood that many modifications may be made to the specific preferred embodiment described herein, in addition to those specifically recited herein, without departure from the spirit and scope of the invention as set forth in the following claims.

The invention claimed is:

1. A food container comprising:

a first portion having a bottom panel, two oppositely disposed first sidewall panels, a first front panel, and a first rear panel;
a second portion having a top panel, two oppositely disposed second sidewall panels, a second front panel, and a second rear panel, and
a hinge portion coupled to said first portion along a first fold line and coupled to said second portion along a second fold line for pivotal movement of said second portion relative to said first portion between a closed configuration wherein said second portion is in register with said first portion and an open configuration wherein said second portion is not in registered with said first portion, said hinge portion forming a panel extending between said first portion and said second portion when said second portion is positioned in its open configuration, said panel of said hinge portion having at least one condiment container opening therethrough of a select opening configuration.

2. The food container of claim 1 further comprising a condiment container having a select container configuration corresponding to said select opening configuration of said condiment container opening.

3. The food container of claim 2 wherein said condiment container has a peripheral rim larger than said select configuration of said condiment container opening.

4. The food container of claim 1 wherein said hinge portion includes a central fold line dividing said hinge portion between a first hinge portion and a second hinge portion.

5. The food container of claim 4 further comprising an adhesive for releasably holding said first hinge portion to said second hinge portion.

6. The food container of claim 1 wherein the hinge portion is temporarily coupled to the rear wall of either the top portion or bottom portion.

7. The food container of claim 6 wherein the hinge portion has a two parts, and wherein one part of the hinge portion is temporarily coupled to the rear wall of the top portion and the other part of the hinge portion is temporarily coupled to the rear wall of the bottom portion.

8. A food container comprising:

a bottom portion having a bottom panel, at least four sidewall panels extending from said bottom panel along bottom panel fold lines, and a separator panel mounted for pivotal movement between a closed position flush with one said sidewall panel and an open position distal said one sidewall panel, said separator panel having a central panel having a bottom central panel fold line extending along one said bottom panel fold line to form a trough between said central panel and one side sidewall panel and at least one end panel extending from said central panel, said at least one end panel

having a bottom edge configured to abut said bottom panel of said bottom portion when said separator panel is in its open position;
a top portion having a top panel and at least four sidewall panels extending from said top panel, and
a hinge pivotally coupling said top portion to said bottom portion.

9. The food container of claim 8 wherein said separator is coupled to said floor panel of said bottom portion.

10. The food container of claim 8 wherein said separator is coupled to one of said four sidewall panels of said bottom portion.
